UNITED STATES PATENT OFFICE.

JACOB HANSEN, OF CHRISTIANIA, NORWAY.

APPARATUS FOR ELECTRICAL STERILIZATION OF FOOD.

1,231,883.

Specification of Letters Patent.

Patented July 3, 1917.

Application filed October 7, 1916. Serial No. 124,262.

To all whom it may concern:

Be it known that I, JACOB HANSEN, citizen of Norway, residing at Christiania, Norway, have invented new and useful Improvements in Apparatus for Electrical Sterilization of Food, of which the following is a specification.

It is a well-known fact that foods are sterilized by being treated with electricity, for instance with alternating current of a high voltage. After such a treatment the goods may be stored for a longer time in a fresh condition. Specially for killing bacteria on split cod the electrolyzation is suitable.

The present invention has for its object to provide a simple and suitable apparatus of the kind referred to and is illustrated in the accompanying drawings, in which:

20 Figure 1 shows the whole apparatus in side view.

Fig. 2 shows on a larger scale a cross section on the line I—I in Fig. 3, seen in the direction of the arrows at the section-line.

25 Fig. 3 is a part of a side view of the apparatus.

The fish is thrown into a hopper —1— (Fig. 1) and passes down into an inclined channel —2— forming a continuation of the hopper. The treatment with electricity takes place during the passing down on the bottom —5— of the channel —2— during the short length of time of passing by and between a number of contact springs —13— 30 and a contact plate —7— (see Fig. 3) embedded in insulating substance —6—. The said plate —7— is connected to one terminal of the secondary —8— (Fig. 2) of an induction coil by means of a screw —9—. The other terminal is connected to a ring —10— 35 attached to a metal shaft or pipe —11— journaled in pairs of clamping pieces —12— and carrying within the channel a large number of very yielding contact springs or 40 members —13—. Each pair of clamping pieces —12— is adjustable in the space —14— between the two insulating rails —15—, 45 16— and is by screws —17— with hand nuts —18— clamped fast in the desired position.

50 In this manner the springs —13— may be brought in the position relatively to the plate —7— most suitable to the size (thickness) of the fish. Also the hopper —1— and the channel —2— may be fixed at a suitable inclination. This is effected by means 55 of clamping screws —19— (Fig. 1) passing

through a guiding strap —20— attached to the side of the hopper and pressing upon a bar —21— which projects through the strap. The lower end of the bar is pivotally connected to the carrying bracket —22— of the apparatus, and to this bracket the lower portion of the channel —2— is hinged as shown in Fig. 1.

The handles —24—, which are made of insulating material and attached to the pipe —11— by means of cross pins —25—, are intended for the adjustment of the spring members —13—. —27— designates a stop ring and —26— the primary of the induction device.

Of course more bottom contacts may be arranged, so that the fish during its passing down through the channel is subjected to a repeated electric treatment.

Furthermore, the fixed bottom contact —7— may be replaced by a large number of springy contact fingers —3— (Fig. 1) attached to the pipe —4— like the corresponding parts —13— and —11— respectively of the top contacts.

Having now described my invention, what I claim as new and desire to secure by Letters Patent is:

1. In an apparatus for sterilization of foods by electric current of high voltage, especially for killing mite, spores and noxious bacteria on split cod, the combination of an inclined channel, a number of bottom contacts in said channel, a number of top contacts arranged opposite the bottom contacts, a source of electricity of high voltage, and connections between the source and the contacts in such a manner that the fish, etc., during its passage down within the channel passes between the said contacts and is thereby subjected to the electric treatment.

2. In an apparatus for sterilization of foods by electric current of high voltage, especially for killing mite, spores and noxious bacteria on split cod, the combination of an inclined channel, contact plates embedded in insulating material in the channel bottom, a large number of yielding springs or yieldingly arranged contact members or fingers projecting into the channel opposite the bottom contacts, a source of electricity of high voltage, and connections between one terminal of said source and the bottom contact plates, and connections between the other terminal and the said members or fingers in such a man-

- ner that the fish, etc., during its passage down within the channel passes between the said contacts and is thereby subjected to the electric treatment.
- 5 3. In an apparatus for sterilization of foods by electric current of high voltage, especially for killing mite, spores and noxious bacteria on split cod, the combination of an inclined channel, a number of yielding springs or yieldingly arranged contact members or fingers in the bottom of the channel, a large number of yielding springs or yieldingly arranged contact members or fingers projecting into the channel from the top of the same opposite the bottom contacts, a source of electricity of high voltage, and connections between one terminal of said source and the bottom contact members, and connections between the other terminal and the top contact members in such a manner that the fish, etc., during its passage down within the channel passes between the said contacts and is thereby subjected to the electric treatment.
- 10 4. In an apparatus as claimed in claim 2 or 3, the arrangement of a turnable shaft
- (11) adjustable along the channel, the yielding contact members or fingers (13) being attached side by side on the said shaft, so that by turning and by longitudinal adjustment of the shaft the top contact members may be adjusted relatively to the bottom contact or members (7 or 3).
5. In an apparatus as claimed in claim 4, the arrangement of clamping pieces carrying the shaft (11) and mounted adjustably between and along two rails (15, 16) which may be clamped fast by screws.
6. In an apparatus as claimed in claim 1, the arrangement of a carrying bracket, to which the lower portion of the apparatus is hinged, whereas the upper hopper-shaped part may be adjusted in height direction and fixed by means of a clamping device (21, 20, 19).
